UNITED STATES PATENT OFFICE

156,060

DESIGN FOR AN INHALANT THERAPY MASK

William T. Wade, Los Angeles, Calif.

Application July 6, 1948, Serial No. 147,393

Term of patent 14 years

(Cl. D83—1)

To all whom it may concern:

Be it known that I, William T. Wade, a citizen of the United States, residing in the city and county of Los Angeles and State of California, have invented a new, original, and ornamental Design for an Inhalant Therapy Mask, of which the following is a specification, reference being had to the accompanying drawing, forming part thereof.

Fig. 1 is a perspective view of an inhalant therapy mask, showing my new design with head strap attached.

Fig. 2 is a front elevation with the head strap removed.

Fig. 3 is a right side elevation of the device as shown in Fig. 2 showing the air inlet and elastic valve outlet both of which appear on this side only of the device.

Fig. 4 is a rear elevation thereof.

I claim:

The ornamental design for an inhalant therapy mask, substantially as shown and described.

WILLIAM T. WADE.
